(57) **CLAIM**

The ornamental design for a barbecue lid trim, as shown and described.

DESCRIPTION

FIG. 1 is an upper-left side perspective view of a barbecue lid trim showing my new design;

FIG. 2 is a left side view thereof;

FIG. 3 is a top plan view thereof;

FIG. 4 is a rear view thereof;

FIG. 5 is a front view thereof; and,

FIG. 6 is a bottom view thereof.

The details shown in broken lines form no part of the claimed design.
